CLAIM

The ornamental design for an electronic gaming machine display screen or portion thereof with a graphical user interface, as shown and described.

DESCRIPTION

FIG. 1 is a front view of an electronic gaming machine display screen or portion thereof with a graphical user interface (GUI) showing the first image in a sequence; and, FIG. 2 is a front view thereof showing the second image in the sequence.

The appearance of the GUI sequentially transitions between the images shown in FIGS. 1-2, with the left edge of the screen portions remaining stationary and providing a common point of reference between FIGS. 1-2. The process or period in which one image transitions to another image forms no part of the claimed design.

The outer dot-dash lines shown in FIGS. 1-2 illustrate the perimeters of screen portions and form no part of the
